(57) **CLAIM**

The ornamental design for a garbage can as shown and described.

DESCRIPTION

FIG. 1 is a top perspective view of a garbage can showing my new design;

FIG. 2 is a bottom perspective view thereof;

FIG. 3 is a front elevational view thereof;

FIG. 4 is a rear elevational view thereof;

FIG. 5 is a left view thereof;

FIG. 6 is a right view thereof;

FIG. 7 is a top plan view thereof;

FIG. 8 is a bottom plan view thereof; and,

FIG. 9 is an enlarged portion taken from line 9 in FIG. 1. The broken lines in the drawings depict portions of a garbage can that form no part of the claimed design. The dot dash broken lines depict enlarged boundaries that form no part of the claimed design.
